UNITED STATES PATENT OFFICE.

DICKRAN M. SARKISIAN, OF FOREST HILLS, NEW YORK.

DETACHABLE RING PULLEY BRACKET.

Application filed March 3, 1923. Serial No. 622,488.

To all whom it may concern:

Be it known that I, DICKRAN M. SARKISIAN, a citizen of the United States, and residing at Forest Hills, county of Queens, 5 State of New York, have invented certain new and useful Improvements in Detachable Ring Pulley Brackets, of which the following is a specification.

This invention relates to detachable ring 10 pulley brackets particularly adapted to be applied to curtain rods of conventional design in order to permit the association therewith of a pulley and cord arrangement adapted to function as a means for facilitating the drawing or retracting of the curtain in an expeditious manner.

An important object of the invention is to provide a device of the character mentioned which is so constructed as to permit 20 the same to be readily applied to a curtain rod of conventional design without necessitating a change or alteration in either the device itself or the rod with which it is desired to associate the same.

25 A further object of the invention is to so construct the device that it may be applied to either end of the rod depending upon whether the curtain operating cord is to be operated from one end of the rod or the other as the case may require.

Other objects and certain advantages of the invention will become apparent from the following description when taken in connection with the accompanying drawings in 35 which—

Figure 1 is a plan view of a curtain rod having my invention associated therewith.

Figure 2 is a front elevation of the curtain rod shown in Figure 1.

40 Figure 3 is a view similar to that of Figure 1, showing the pulley brackets reversed.

Figure 4 is a sectional view taken on line 4—4 of Figure 3.

45 Figure 5 is a sectional view taken on line 5—5 of Figure 3.

In the drawings wherein for the purpose of illustration is shown what I at present consider the preferred form of my invention, the numeral 5 indicates a pair of curtain rod supports having bases 6 which are adapted to be secured to a suitable supporting structure such, for example, as a window frame, not shown. These rod supports are bent at right angles at their outer ends 50 as shown at 7 and are provided with ferrules or sockets 8 into which are fitted op-

posite ends of a curtain rod 9, upon which are adapted to slide a plurality of curtain rings 10 provided with eyelets 11 or other suitable means for attaching thereto a pair of depending curtains or portières 12. These curtains are adapted to be drawn or retracted through the instrumentality of a curtain operating cord 13, suitably connected to the curtain rings 10 supporting the innermost 60 or meeting margins of the curtains 12, the operation of the curtains 12 through the instrumentality of the curtain operating cord 13 being well understood by those skilled 65 in the art to which my invention pertains. 70

As a means for facilitating the operation of the curtains through the instrumentality of the curtain cord 13 I provide a pair of pulley supporting brackets 14 and 15 which are adapted to be readily attached to or detached from the outer or bent portions 7 of the curtain rod supports 5. Each of these brackets comprises a yoke 16 adapted to be fitted over the outer portion 7 of the supports as is clearly shown in Figure 4. The 80

yoke 16 comprises a base 17 which is provided with a heel portion 18 and carries at one end a thumb screw 19 which is adapted to be run down into firm engagement with the outer end 7 of the support as shown in 85 Figure 4, thereby firmly locking the bracket in proper position. It will be noted in the case of each bracket that the heel portion 18 and the thumb screw 19 are arranged in a plane intersecting the outer end 7 of the support 5 somewhat at one side of the axis thereof so that once the thumb screw 19 is run down into engagement with the outer end 7 of the support 5 the bracket is securely 90 locked against displacement under all conditions. Both of the brackets 14 and 15 thus far described are identical they being different however in certain particulars as will hereinafter more readily appear. The base 15' of the bracket 14 is provided with a pair 95 of depending arms 20 and an intermediate depending arm 21, which arms function as supports for a shaft 22 upon which are mounted pulleys 23 over which the curtain cord 13 is adapted to operate. The bracket 100 15' being somewhat different in certain details from the bracket 14, is provided with a depending arm 24 having a laterally disposed finger 25 arranged in a parallel relation with respect to a similar finger 26 carried by the base 17. These fingers support 105 a transversely disposed shaft 27 upon which

is rotatably mounted a pulley 28 over which the curtain cord 13 is adapted to operate. By pulling one end of the curtain cord 13 the curtains 12 may be separated whereas 5 by pulling the other end of the curtain cord the curtains may be drawn together as shown in Figure 2, as will be readily appreciated by those skilled in the art to which my invention relates. With the brackets 14 and 10 15 positioned with respect to the curtain rod 9 as shown in Figure 2, the curtain cord 13 is adapted to be operated from the right hand side of the curtains, but should conditions be such that right hand operation is 15 impracticable the position of the brackets 14 and 15 may be reversed as shown in Figure 3. This reversal is made possible with the standard form of curtain rod or curtain rod support by reason of the fact that their construction 20 is such that they may be readily detached from or attached to either of the curtain supports 5 at opposite ends of the curtain rod thus obviating the necessity of a change in construction of the brackets 25 themselves or the curtain rod supports to meet a particular requirement.

Having thus described my invention I claim:

1. The combination with a support, of a 30 pulley bracket comprising a yoke adapted to embrace said support, said yoke terminating at one end in a locking heel, and locking means carried by the other end of said yoke and adapted to cooperate with said 35 heel for anchoring said bracket to said support.

2. The combination with a support, of a

pulley bracket comprising a yoke adapted to embrace said support, said yoke being provided with a locking heel, and locking means adapted to cooperate with said support for anchoring said bracket thereto, said heel portion and locking means being disposed in a common plane passed longitudinally through said support at one side of the axis thereof. 40 45

3. The combination with a support of a pulley bracket comprising a yoke adapted to receive said support, one end of said yoke terminating in a heel portion, and locking means carried at the opposite end of said yoke and adapted to cooperate with said heel portion for locking said bracket to said support. 50

4. The combination with a support, of a pulley bracket comprising a yoke adapted to receive said support, one end of said yoke terminating in a heel portion, and a screw carried at the opposite end of said yoke, said screw and heel portions being disposed in a common plane passed longitudinally 60 through said support at one side of the axis thereof.

5. A pulley connector for curtain rods comprising, a rigid main frame having a passage therethrough open at one side to receive a rod, and to permit said frame to be applied to said rod from the side thereof, a pulley carried by said frame, and means for firmly securing said frame on a rod in various positions of angular and longitudinal adjustment, and against movement thereon. 65 70

In testimony whereof, I have affixed my signature to this specification.

DICKRAN M. SARKISIAN.
